Samuel Fairlamb & John S. Gilpin
8722 X Letters Patent

The Schedule referred to in these Letters Patent and making part of the same containing a description in the words of the said Samuel Fairlamb & John S. Gilpin themselves of their improvement in an Inking Machine for inking types &c.

The Machine is composed of a cast iron frame having two upright sides or posts, which support the inking roller, a vibrating and distributing roller, a distributing roller and the ink trough or fountain with its roller and scraper. In the rear of the frame there is an upright arm or lever having a horizontal axis at its lower end which rests on a carrier and permits the arm or lever to oscillate; and on this axis are attached two horizontal levers extending in opposite directions, one toward and the other from the front to which the machine may be attached. The one extending from it is permanently fixed on the axis but the other is loose at its fulcrum which is the axis and has a crooked lever loosely attached to its side by a pivot bolt the shortest end next to the upright arm or lever being hooked. The two first of these levers have caps on their ends to hold weights, and to the end of the one extending toward the front a cord is attached which passes over a pulley to the rounce of the cast iron where it is fastened. A cord is likewise attached to the end of the other lever which passes over a pulley fixed on a carrier in the rear, and has a weight fastened to its end. At the upper end of the upright arm or lever is attached by a joint the handle of the frame of the inking roller, all which is nearly in the form of those commonly used with a hand roller except that the frame moves on friction wheels. On the side of the upright part of the frame, which is next to the platter of the press, there is affixed on carriers a rounce, from which straps extend in contrary directions and are fastened to each end of the bed of the press, there are two cords passing around the rounce and to one end of the driving, & vibrating roller, which is in the form of a screw, and around which the cords wind in opposite directions; the end of a pin which is permanently fixed in the frame is made to enter the groove of the screw on this roller and causes it to vibrate when in motion. The inking roller with its frame & handle rests on two

wheels permanently fixed on the frame of the machine above the vibrating and driving roller coming in contact with it and is held to its place by a spring hetch on the frame entering not having its frame. A small distributing roller which receives the ink from the cylinder in the ink trough is in contact with the driving & vibrating roller & is pressed to it by springs; below this roller is the rear of the driving roller, the ink trough rests on journals in carriers on the frame and has a metal cylinder in it resting on its journals (and partly immersed in ink); it has a ratchet wheel on the out end of one journal into the teeth of which a dog fastened on the frame enters and effects its revolution when in motion, A scraper or regulator is fixed on the ink trough to regulate the ink on the cylinder, It is made of a thin piece of spring steel or other metal having similar qualities and is about three inches wide and as long as the cylinder.

One side of it is fastened by screws or rivets to a piece of metal of nearly the same width and length (and about half an inch thick). The other side of the scraper is loose from the piece of metal (and) projects somewhat beyond its edge. The piece of metal near to its edge has screws passing through it, their lower ends coming in contact with the upper surface of the steel scraper and near to its edge, (and) both are secured to the wkh trough by screws in such a manner that a cord of about sixty degrees drawn on the semicircle of the cylinder in the wkh trough will form the line of direction of the edge of the scraper when pressed on by the screws in the piece of metal to which it is attached though it may be set to any other angle found convenient, so that its tendency is not directly to the centre of the cylinder. To regulate the wkh on the cylinder the screws are made to press more or less on any part of the edge of the scraper as may be found necessary. A lever is fastened to the back part of the wkh trough to the end of which a cord is attached which passes round a pulley beneath it, and then to the upright arm or lever which in its movement causes the wkh trough to oscillate. The machine is operated by the movement of the back of the prop by means of the straps attached to it and the rounce of the machine. The cord extending from the rounce of the machine to the end of the lever next the prop to which the loose lever is attached is leveled both so that the hooked end of the loose lever takes hold of a pin in the lower part of the upright arm or lever, (and) the weight on the end of the first mentioned lever descending carries the upright arm or lever

8722 X

over forward, (and with it the inking roller &c.) When this weight and lever have descended far enough the end of the crooked (and loose) lever meets a prominent fixture which detaches it from the upright arm or lever when the weight on the permanent lever in the opposite direction carries it (and with it the inking roller &c.) to their first position, where they are held by the spring catch on the frame entering notches in the frame of the ink roller (and from which it is relieved by the limpan when being raised striking & holding back said catch. The ink is distributed on all the rollers by the driving and vibrating roller which is attached to the source of the machine by cords; it having been first communicated to the small distributing roller by the movement of the ink troughs &c.)

What we claim as of our invention is the application or manner of applying an elastic scraper to effect the regulation of printing ink on a cylinder or roller, and the manner of applying granulating substances or heavy bodies to propel an inking roller over a form of type &c &c.
